UNITED STATES PATENT OFFICE.

HORACE L. PATTERSON, OF OTISVILLE, NEW YORK, ASSIGNOR TO THE ADAPTO MFG. CO., INC., OF OTISVILLE, NEW YORK, A CORPORATION OF NEW YORK.

MOTOR-HYDROCARBON-SUPPLY DEVICE.

1,222,576.

Specification of Letters Patent. Patented Apr. 10, 1917.

Application filed May 20, 1916. Serial No. 98,754.

To all whom it may concern:

Be it known that I, HORACE L. PATTERSON, a citizen of the United States, residing at Otisville, in the county of Orange and State 5 of New York, have invented certain new and useful Improvements in Motor-Hydrocarbon-Supply Devices; and I do hereby declare the following to be a full, clear, and exact description of the invention, such as 10 will enable others skilled in the art to which it appertains to make and use the same.

This invention relates to a device for supplying hydro carbon to gas engines, and has for one of its objects the provision of a 15 device which is capable of being applied to any type of gas engine but is more particularly designed for use in connection with automobile engines.

Another object of this invention is the 20 provision of means for readily controlling a supply of hot air and hot water or steam, to the carbureter, by the operation of a single lever within easy reach of the operator.

A further object of the invention is to 25 position a hot air hood over the exhaust manifold of the engine and to run a water pipe from a suitable source of supply through this hot air hood to the carbureter whereby the water may be converted into hot 30 water or steam in its passage through the hood to the carbureter.

A still further object of this invention is 35 the provision of novel means for heating the air and the water by the exhaust manifold of the engine.

These and other objects and advantages 40 will more fully appear as the nature of the invention is more clearly understood from the following specification, the subject matter of the claim, and the views illustrated in the accompanying drawings, in which,

Figure 1 is a side view of the front portion 45 of a motor vehicle, partly broken away and shown in section, showing the invention in applied operative position thereon.

Fig. 2 is a side elevation of the valve casing employed, the operating stem for the valve therein being shown as partly broken away.

50 Fig. 3 is a transverse sectional view, on line 3—3 of Fig. 2, showing the detail construction of the valve casing and the valve operating therein.

Referring to the drawings, wherein similar reference characters denote correspond-

ing parts throughout the several views, 1 denotes the front wheel, 2 the engine hood, 3 the dash board, 4 the foot board, and 5 the seat of an automobile or other motor vehicle and within the engine hood 2 is the engine 6 60 provided with the exhaust branch pipes 7 connecting the engine cylinders with the exhaust manifold 8, the intake manifold 9, and the carbureter 10, these parts being those of any well known form of engine. 65

For supplying hot air to the carbureter 10, the upwardly extending hot air pipe 11 is suitably secured to the carbureter 10 and is provided at its upper end with the elongated hood or casing 12 provided with the corrugated or scalloped portions so that the bottom of the hood or casing 12 will rest upon and partially embrace the branch pipes 7 of the exhaust manifold 8, the corrugated or scalloped bottom 13 of the bottom of the 75 hood or casing 12 project downwardly between the branch pipes 7 and between the exhaust manifold 8 and the engine 6, so that the air passing through the open end 14 of the hood or casing 12 is efficiently heated by 80 the exhaust branch pipes 7, the exhaust manifold 8 and the adjacent side of the engine 6, whereby the air passes from the hood or casing 12 through the hot air pipes 11 to the carbureter 10 in thorough heated condition, and for supplying the liquid fuel to the carbureter 10 the main fuel supply pipe 15 is provided. 85

Suitably positioned beneath the seat 5 of the vehicle is the tank 16 for containing pure 90 gasoline, the tank 16 being provided with the gasoline supply pipe 17 and also suitably positioned beneath the seat 5 is the tank 18 for containing kerosene or a mixture of kerosene and gasoline, the kerosene and 95 gasoline being mixed in any suitable proportions, but preferably mixed at a ratio of three parts kerosene to one part gasoline, although in certain motors pure kerosene may be used without the gasoline, and for 100 the sake of clearness and convenience the tank 18 will be hereinafter described as the kerosene tank to avoid confusion, the kerosene tank 18 is provided with the kerosene supply pipe 19. 105

For supplying hot water or steam to the carbureter 10 the water tank 20 is provided and positioned preferably at the left hand side of the engine at a point on the horizontal plane with the carbureter 10 or below 110

this plane but not above a plane with the carbureter for the purpose of avoiding siphonage of the water therein when the engine is at rest, and for conveying the water 5 from the tank in the direction of the engine the water pipe 21 having its intake end positioned within the tank in proximity to the bottom thereof, and at a point remote from its intake end the water pipe 21 projects 10 upwardly into the hood or casing 12 and projects therethrough from end to end providing the hot water heater or steam generating portion 22 and projects from the opposite end of the hood or casing 12 to 15 provide the steam pipe 23 which has its free end suitably secured to the carbureter 10 for injecting steam into the mixing chamber therein and provided with the valve 24 for regulating the flow of the hot water 20 or steam, the discharge end of the steam pipe 23 being secured and positioned in the carbureter at a point just back of the controlling damper in the carbureter.

For controlling and regulating the supply 25 of gasolene, the supply of the mixture of kerosene and gasolene, and the supply of water, to the engine, there is interposed between the gasolene supply pipe 17, the kerosene supply pipe 19, the fuel supply pipe 15, 30 and in the water pipe 21, the valve casing 25 provided with the nipple 26 having the port 27 therethrough, the nipple 28 having the port 29 therethrough, the nipple 30 having the port 31 therethrough, and the nipple 32 35 having the port 33 therethrough, the gasolene supply pipe 17 being secured to the nipple 26, the fuel supply pipe 15 leading to the carbureter 10 being secured to the nipple 28, the kerosene supply pipe 19 being secured 40 to the nipple 30, and the drain pipe 34 being connected to the nipple 32 and provided with the drain valve 35. The nipples 26, 28, 30, and 32 of the valve casing 25 are positioned upon the periphery of the valve 45 casing in proximity to its upper end and at points substantially ninety degrees apart. The valve casing is also provided with the oppositely disposed nipples 36 having ports therethrough and to the nipples 36 are secured the adjacent ends of the water pipe 50 21. The nipples 36 are positioned upon the valve casing 25 at points in proximity to the lower end of the valve casing 25 and in alinement with each other considerably off center or to one side of the diameter of the 55 valve casing 25.

Rotatably mounted within the valve casing 25 is the valve 37 provided with the threaded stem 38 which is engaged by the 60 plate nut 39 and washer 40 for securing the valve 37 within the valve casing 25. The valve 37 is provided with the radial port 41 and the radial port 42, the inner ends of the ports 41 and 42 communicating with each 65 other and the ports being disposed in right

angular relation to each other with their outer ends substantially ninety degrees apart. The ports 41 and 42 are formed at a point in proximity to the upper end of the valve 37 for adapting the ports 41 and 42 70 to be brought into registration with the ports 27, 29, 31, and 33 of the valve casing 25, and also formed through the valve 37 at a point in proximity to its lower end and adapted to be brought into registration with the ports of the nipples 36 is the port 43 also disposed at one side of the diameter of the valve 37 or offset from its longitudinal axis. The valve 37 is provided at its upper end with the operative lug 44 to which is connected by the bolt 45 the fork 46 of the valve operating stem 47 which passes upwardly through the aperture 48 of the foot board 4 and has its upper end revolvably mounted in the bracket 49 secured upon the rear side of the dash board 3, the upper end of the valve operating stem 47 is provided with the operating lever 50, and secured upon the stem 47 below the lever 50 is the pointer 51 for coacting with the dial plate 52 secured upon the upper surface of the bracket 49 for indicating the respective adjustments of the valve 37 and the relative positions of its ports with the ports of the valve casing.

After the engine has been running a sufficient length of time to efficiently heat the engine and its manifold exhaust, the operator turns the lever 50 for positioning the valve 37 in the position shown in Fig. 3, whereby the kerosene in the tank 18 will 95 now flow through the pipe 19 through the valve casing and valve and the main fuel pipe 15 to the carbureter 10 thereby becoming aerated by the hot air from the hot air pipe 11 which air has been heated in its passage through the hood or casing 12. At the same time water is drawn from the tank 20 through the first section of the pipe 21 within the heated hood or casing 12 where the water is heated or converted into steam 100 105 and issues from the generating portion 22 through the steam pipe portion 23 of the pipe 21 and is injected into the vaporized kerosene in the carbureter 10.

Should it be desired to drain the kerosene 110 from the tank 18, or the gas from the tank 16, the handle 53 is rotated to actuate the controlling valve whereby either kerosene or gas may be drained from the discharge or drain pipe 34.

Another feature being in the specific construction of the hood or casing 12 and its manner of contact with the engine cylinders, the exhaust branch pipes and the exhaust manifold of the engine, whereby the 125 air is efficiently heated in its passage through the hood and the water pipe passing through the hood is also heated to a sufficient degree to convert the water passing therethrough into a sufficiently heated state or steam for 130

use in connection with the mixture of kerosene and gasolene, or kerosene alone.

While the preferred embodiment of the invention is herein illustrated and described, 5 minor alterations and variations may be made therein from time to time to meet the exigencies of the case without departing from the spirit of the invention or the scope of the claim.

10 Having described my invention, what I claim as new and desire to secure by Letters Patent, is:—

15 In a motor vehicle, the combination with the engine, exhaust manifold, and the carbureter thereof, of a hood disposed over said exhaust manifold, a hot air pipe leading from said hood to said carbureter; a hydro-

carbon supply pipe for the carbureter, a water supply tank, a water pipe leading from said tank through said hood and then 20 downwardly to the carbureter, and means for controlling the admission of water to said pipe, the water in its passage through the water pipe disposed within the hood adapted to be converted into steam and conveyed to the carbureter. 25

In testimony whereof I have signed my name to this specification in the presence of two subscribing witnesses.

HORACE L. PATTERSON.
